UNITED STATES PATENT OFFICE.

HUGO H. WERMINE, OF CHICAGO, ILLINOIS, ASSIGNOR TO BELDEN MANUFACTURING COMPANY, OF CHICAGO, ILLINOIS, A CORPORATION OF ILLINOIS.

INSULATING TUBE AND PROCESS OF MAKING SAME.

Application filed April 15, 1922. Serial No. 553,286.

My invention relates to improvements in insulating tubes and process of making same, and has particular value in the manufacture of sleeving employed as an insulator for lead 5 wires.

The principal object of the invention is to provide an improved insulating tube or sheathing which may be manufactured at relatively low cost, which shall have high dielectric strength, which shall be form-sustaining, substantially waterproof and through which bare or other wires may readily be inserted.

In the drawings accompanying this application:

15 Fig. 1 is a diagrammatic elevation of apparatus which may be employed for manufacturing my improved tube;

Fig. 2 is a section taken on the line 2—2 of Fig. 1; and

20 Fig. 3 is a section taken on the line 3—3 of Fig. 1.

Heretofore it has been the practice, in general, to use two different forms of insulating tubes for removably containing wires leading 25 to the terminals of the electric coils or analogous apparatus. Braided sleeving has been used to a considerable extent, but such sleeving has the disadvantage that it is not form-sustaining, and, also, although attempts have been made to treat same with 30 varnish, the dielectric strength of the sleeving has been relatively low.

There also has been used what in the trade is known as "Itala" tubing, this consisting 35 of a continuous tube of linen impregnated or otherwise treated with a material of high dielectric strength. However, this "Itala" or "Empire" tubing up to the present time has usually been imported at great cost, and 40 its use on that account has been confined to relatively expensive apparatus.

In producing tubing according to my invention, any desired form of apparatus may be employed, but I prefer to use apparatus 45 similar to that shown in the drawings. In such drawings I have illustrated diagrammatically two spools 10 of any desired type of braiding machine, it being understood that the machine is equipped with eight, twelve, sixteen or any other customary number of 50 spools, the paths of which spools in traveling around the center of the machine cross each other, thus forming the interwoven braid effect.

55 At the center of the machine and just be-

low where the laying on of the braiding threads 11 occurs, in place of the ordinary guide I equip the machine with a die 12 having a tapering bore 13, the lower end of the bore being considerably greater in diameter 60 than the upper end of the bore. Below the bottom of the die 12 I preferably use a pre-forming die 14, said die being cut in two parts, as shown in Fig. 2, the two parts of the die being spaced by a vertically extending channel 15 of sufficient width and thickness to accommodate the insulating strip 16.

The insulating strip 16 consists of a continuous length of insulating tape, preferably waterproof material such as bias-cut varnished cambric. Said insulating strip 16 is fed from a suitable spool 17, and as it is drawn through the channel 15 of the die 14, it is preformed so that it will readily enter into the lower end of the bore 13, the upper portion of which completes the folding or coiling of the strip into the form of a round tube 18. As shown in Fig. 3, said tube 18 is formed with its edges overlapping to the extent of approximately 100% of a complete convolution, the seam of the tube being longitudinal rather than spiral, whereby stretching is avoided.

It will be understood that in the absence of further treatment the tube 18, having been 85 formed without the aid of cement or other material for uniting together its overlapping ends, by reason of the inherent resiliency of the material, would immediately spring open and again assume the shape of a strip. This 90 opening up of the tube is, however, prevented by applying to the tube, at the point where it emerges from the upper end of the die 12, a close fitting braid 19 by means of the braiding apparatus heretofore referred to. A capstan 95 20 of usual construction is employed to propel the tube through the die at a speed regulated in accordance with the speed of application of the braid.

The braided tube, after it leaves the braiding machine, is conducted into a bath of insulating cement or varnish which impregnates the braid, but on account of the imperviousness of the strip material, does not penetrate to the interior of the tube. The impregnated 100 braid is subsequently dried, either in the air if the varnish is of the air drying type, or in a suitable oven if the varnish is of the baking type, said drying being preferably carried on as a continuous process.

The completed article fully meets the requirements, as it possesses an extremely high dielectric strength. It is non-collapsible and form-sustaining, having a smooth interior 5 surface which does not interfere with the insertion of the conductors. It will withstand a large amount of abuse, and is relatively cheap as compared with the Italian tubing which it effectually displaces.

10 The details of description and operation are merely illustrative of a single phase of my invention, the scope of which should be determined by reference to the appended claims, said claims being construed as broadly as possible consistent with the state of the art.

I claim:

1. In a non-metallic conduit, the combination of an inner lining comprising a single 20 strip of flexible insulating material coiled cross-wise of the length thereof, to form a cross-sectionally spiral, multi-walled tube,

the edges of the strip being disposed lengthwise of the tube, and a braided cover over said tube for preventing uncoiling thereof. 25

2. In a non-metallic conduit, the combination of an inner lining comprising a strip of flexible insulating material coiled cross-wise of the length of the strip to form a double and cross sectionally spiral walled tube, the 30 edges of the strip being disposed lengthwise of the tube, and a braided cover over said tube for preventing uncoiling thereof.

3. The process of manufacturing non-metallic conduit of the class described, which 35 process consists in longitudinally propelling a strip of flexible insulating sheet material, coiling same cross-wise of its length to form same into a tube having substantially double walls forming a spiral in cross section of the 40 tube, and then applying a fabric covering to prevent uncoiling of said tube.

HUGO H. WERMINE.
